UNITED STATES PATENT OFFICE.

THOMAS NATHAN RUSSELL, OF CHICAGO ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed January 9, 1924. Serial No. 685,260.

This invention relates in general to railway car roof constructions and more particularly to improvements in the all steel rigid type of car roofs.

Objects of the invention are the provision of an all steel rigid roof which may be readily and easily assembled, involves comparatively few parts, is easily and inexpensively manufactured, and affords a plurality of bracing elements and weather-tight joints without requiring caps for the joints or other closure members; the provision of a construction requiring comparatively few rivets but attaining strength and rigidity of the roof; and the provision of a construction having simple, compact closed seams, together with such other objects and advantages of the invention as are found to obtain in the structure hereinafter set forth and claimed.

In the accompanying drawings forming a part of this specification, and showing, for purposes of exemplification, a preferred form and manner in which the invention may be embodied and practiced, but without limiting the claimed invention specifically to such illustrative instance or instances:

Figure 1 is a partial top plan view of a portion of the car roof embodying my invention.

Fig. 2 is a section taken on the line 2—2 of Fig. 1.

Fig. 3 is a partial longitudinal section taken through the ridge of the roof showing the end roof sheet section secured to the end of the car.

Fig. 4 is a cross section taken on the line 4—4 of Fig. 1.

Fig. 5 is a vertical cross section taken through the eaves of the car showing carline and roof sheet secured to a metallic side plate.

Fig. 6 is a view similar to Fig. 5 but showing the manner of securing the carlines and roof sheets to a wooden side plate.

Fig. 7 is a vertical cross section taken on the line 7—7 of Fig. 1.

Fig. 8 is a section taken on the line 8—8 of Fig. 1 showing the manner of lapping and securing adjacent roof sheet side flanges.

Fig. 9 is a top plan view of an intermediate roof sheet section.

Fig. 10 is a side elevation of the same.

Fig. 11 is a section taken on the line 11—11 of Fig. 9.

Fig. 12 is a top plan view of an end roof sheet section.

Fig. 13 is a section taken on the line 13—13 of Fig. 12.

Fig. 14 is a top plan view of a portion of one of the carlines.

Fig. 15 is a side elevational view of the same.

Fig. 16 is a perspective view of the running board saddle.

The upper part of the car body, which is the supporting framework of the car, consists of side plates, formed as either metallic members 10 or wooden members 11, and carlines 12, and metallic end plates 13. In the present instance, the metallic side plates consist of a depending portion 14 and an outwardly extending inclined top flange 15, extending longitudinally of the car. The end plates 13 are bent at their upper portion to provide an inwardly projecting flange 16 extending from side plate to side plate.

The carlines 12, in the present instance, are of inverted channel shape and conform to the pitch of the roof, said carlines consisting of a top web 17 parallel with the roof sheets that engage over them, and depending side flanges 18.

The side flanges 18 at each end of the carlines are bent laterally at 19 to engage the depending portion of the metallic side plates and are rigidly secured thereto as by rivets 20. The top web of the carline is continued outwardly at the end to provide an extension 21 for engaging the inclined top flange of the side plate and it is rigidly secured to the latter by rivets 22.

As shown in Fig. 6 the carline is secured to a wooden side plate in much the same manner as above described, except that extension 21 is omitted and the top web is depressed at 23 to receive the top flange 24 of a metallic plate 25 that has a depending portion 26 fitting between the wooden side plate and the laterally extending flanges 19 of the end adjacent of the carline.

This top flange 24 is secured to the top web of the carline by rivets 27 and the depending portion is secured between the wooden side plate and the flanges 19 by bolts 28.

Intermediate metallic roof sheets 29 are

105

formed as shown to conform to the pitch of the roof. They extend clear across the car from eaves to eaves and their ends terminate in depending eaves flanges 31. The 5 eaves portions of the roof sheets are rigidly secured to the side construction of the car as by rivets 32 passing through said sheets and the top flange 15 of the metallic side plates 14. The roof sheets are secured to 10 the side construction shown in Fig. 6 by bolts 28 that pass through the depending eaves flanges 31 of the roof sheets and the wooden side fascia 33 and side sheathing 34 and side plate 11.

15 One side of the roof sheets 29 is bent upwardly at 35 to provide a vertically or upwardly projecting flange 36 that extends from side to side of the car longitudinally of the sheet. The opposite side edge of the 20 sheet is bent at 37 to provide a vertically extending flange 38 consisting of an upwardly extending wall 39 rebent at 41 to provide a downwardly extending wall 42 spaced from the wall 39; and the wall 42 terminates 25 in an outwardly or laterally extending flange 43 that lies on the main body of the next adjacent roof sheet and is parallel therewith. When the roof sheets are assembled, the flange 38 is fitted over the flange 36 of the 30 next adjacent roof sheet and these flanges are rigidly secured together as by rivets 44 thereby providing a beam element constituting a closed compact joint which is very strong and rigid and water-tight and yet is 35 easily manufactured and assembled.

The main body of each of the roof sheets is provided with a raised portion 45 that is pressed out of the plane of the main body of the sheet. This portion extends longitudinally of the sheet and fits over the top web of the underlying carline to which it is rigidly secured by rivets 46. This pressed out portion 45 is located between the side flanges 36 and 38 of each roof sheet. It will 40 be observed from the foregoing that the roof sheet is in metal to metal contact at the eaves of the car at all points and the eaves of the car are very effectively protected against the weather.

50 The running board saddles 47 are substantially Z-shaped in cross section, each being provided with a web 48, transversely extending top flange 49 and bottom flange 51. The bottom flange is inclined from a point 55 52 intermediate its extremities thus providing flanges 53 conforming to the pitch of the roof which are secured by rivets 54 that pass through the portion 45 and the top web of the carline therebeneath. The running boards 55 extend longitudinally of the car over the ridge and are secured to the top flange 49 by bolts 56.

The end roof sheet sections are formed similarly to the intermediate roof sheet sections except that one side edge terminates

in a depending flange 57 that is riveted to the end plate by rivets 58.

The invention as hereinabove set forth is embodied in a particular form of construction but may be variously embodied within 70 the scope of the claims hereinafter made.

I claim:

1. A car roof construction comprising, in combination, side plates, carlines of inverted channel form having a top web and depending side flanges, the side flanges being bent laterally at each end and secured to the side plates, and the top web continuing and being also secured to the side plates, and metallic roof sheets extending from eaves to eaves and having eaves flanges, each of said roof sheets having a longitudinally extending raised portion disposed substantially midway of the width of the sheet, and said raised portion fitting over the carline 80 therebeneath and being riveted thereto. 75

2. A car roof construction comprising, in combination: side plates; carlines consisting of a top web and depending side flanges secured to said side plates; metallic roof 90 sheets extending from eaves to eaves and terminating in depending eaves flanges; the eaves ends of said roof sheets being rigidly secured on the car side construction; one side edge of each roof sheet having a vertically extending flange, the opposite side edge of said roof sheet being flanged vertically to provide two side walls that enclose the vertically extending flange of the next adjacent roof sheet, said flanges being rigidly 95 secured together, each of said roof sheets having a portion pressed out of the plane of the sheet, said portion being between the said side flanges and extending longitudinally of the sheet and fitting over the said carline therebeneath. 100

3. A car roof construction, comprising, in combination: side plates; carlines; metallic roof sheet sections therefor; said sections extending clear across the car and each having a portion pressed out of the plane of the section extending from side to side of the car, said pressed out portions engaging their respective carlines; the side edges of said sheets being flanged and the flanges of adjacent sheets being lapped one over the other and rigidly secured together. 110 115

4. A car roof construction comprising, in combination side plates; carlines, metallic roof sheets therefor, said roof sheets having their side edges flanged, the flanges of adjacent roof sheets being rigidly secured together, and each of said roof sheets having a portion pressed out of the plane of the sheet between said side flanges, the carlines being secured to said sheets at their pressed out portions. 120 125

5. A car roof construction comprising, in combination: side plates, carlines each having a top portion disposed parallel to an 130

adjacent roof sheet, metallic roof sheets respectively having depending eaves flanges and a longitudinally extending pressed out portion intermediate the side edges of said 5 roof sheets to fit on said top portion of the carline, one side edge of each of said roof sheets being bent upwardly and the other side edge being bent upwardly and the upwardly bent portion being bent downwardly 10 and terminating in a flange parallel with the main body of the next adjacent roof sheet, said last mentioned upwardly and downwardly bent portions enclosing the upwardly bent edge of the next adjacent roof 15 sheet and said edges being rigidly secured together to form a closed compact seam, and the eaves portions of said roof sheets being rigidly held on said side plates.

6. A car roof construction comprising, in 20 combination: side plates, carlines secured

thereto; metallic roof sheets extending across said car from eaves to eaves and rigidly secured thereon; each of said roof sheets having a longitudinally extending raised portion at substantially midway the width 25 of the sheet, said raised portion fitting over the carline therebeneath and secured thereto; one side edge of each of said roof sheets having an upstanding flange extending substantially throughout the length of the 30 sheet; the other side edge of said roof sheet having an upstanding flange for enclosing the upstanding flange of the next adjacent sheet which is formed substantially the same as the upstanding flange first above mentioned, said flanges being rigidly secured together. 35

In testimony whereof I have hereunto set my hand.

THOMAS NATHAN RUSSELL.
